UNITED STATES PATENT OFFICE

2,602,902

SWEEP AMPLITUDE CONTROL FOR MAGNETICALLY DEFLECTED CATHODE-RAY TUBES

Glenn L. Haugen, Baltimore, Md., assignor to Bendix Aviation Corporation, Towson, Md., a corporation of Delaware

Application February 14, 1950, Serial No. 144,139

5 Claims. (Cl. 313—76)

1

This invention relates to a simple and inexpensive means for the control of the sweep amplitude of a cathode ray tube. It lends itself particularly to use for the control of the horizontal width of the picture of a television picture tube.

Necessity for such a width control means arises, for example, in the manufacture of television sets where it is desired to construct receiver assemblies which may be used for either of two sizes of picture presentation. In such cases it is economical to utilize one horizontal deflection circuit for both picture sizes. This can be accomplished by the use of a coil and tuning slug but these components are comparatively expensive and their use entails extra wiring, an extra mounting hole in the chassis and a tap on the horizontal output transformer.

It is an object of the present invention to provide a sweep amplitude control means for magnetically deflected cathode ray tubes which is simple and inexpensive to manufacture and requires no circuit or chassis alteration for its use.

It is another object to provide such a control means which is readily accessible for adjustment from the rear of a television receiver.

It is a further object of the invention to provide such a control means the presence or adjustment of which does not affect the performance of the set other than with respect to the sweep amplitude of the cathode ray tube.

These and other objects of the invention are realized by a split metallic sleeve fitted around the neck of the cathode ray tube beneath the deflection coils and movable longitudinally of the tube to vary the amplitude of its deflection.

Referring now to the drawing:

Fig. 1 is a perspective view of a sleeve embodying the invention, and

Fig. 2 is a side elevational view of a portion of a cathode ray tube showing the sleeve of Fig. 1 in place on the neck thereof and showing the deflection and focus coils in section.

Referring more particularly to the drawing, Fig. 1 shows a cylindrical sleeve 10, of thin sheet metal which may be either magnetic or non-magnetic in character. The sleeve is provided with a longitudinal interruption 11 extending its full length.

In Fig. 2 the sleeve 10 is shown in place on the neck of a cathode ray tube 12 about which it fits snugly. It is shown as extending beneath the deflection yoke 13 for part of the latter's length and as extending through and to the rear of the focussing coil 14 toward the base of the cathode ray tube.

2

In operation the effective sweep amplitude of the cathode ray tube is changed by moving the sleeve 10 longitudinally along the neck of the cathode ray tube to vary the portion of it which underlies the deflection yoke. If the sleeve is made of magnetic material it acts as a magnetic shield to reduce the magnetic field within the tube due to the action of the deflection coils. If it is constructed of non-magnetic material the eddy currents induced in it by the varying magnetic field will also act to reduce the field within the tube. The interruption 11 is necessary in order to prevent the sleeve from acting as a shorted turn for the deflection yoke.

15 The sleeve, if of non-magnetic material, is allowed to project to the rear of the focussing coil to permit it to be easily reached from the rear of the set for adjustment of its position along the neck of the cathode ray tube. It can easily be held in position by tape. A non-magnetic sleeve will not affect the action of the focus coil.

20 A non-magnetic material is preferred since it is more highly conductive. Aluminum is particularly suited for this device since it is light, inexpensive, highly conductive and easily worked.

25 The sleeve 10 is, of course, formed of a strip of sheet metal. If a lesser degree of amplitude control is desired the strip may be narrower, so that it lies only on one side of the tube neck. In this case care must be exercised in positioning the strip with respect to its angular relationship to the horizontal deflecting coils, in order that the shape of the picture will not be distorted.

30 This simple device lends itself well to the selective control of the horizontal width of a television presentation since the horizontal circuits operate at 15,750 C. P. S. whereas the vertical circuits operate at 60 C. P. S. At the higher frequency eddy currents are induced in the sleeve and they oppose the magnetic field of the horizontal deflection coils. Horizontal width can be varied by as much as 25 per cent by sliding the sleeve in or out of the yoke, with a negligible effect on high voltage. The vertical circuits, operating at 35 40 45 50 55

60 C. P. S., are virtually unaffected.

An aluminum sleeve 3.25 inches in length and having a thickness of .005 inch has been found to give satisfactory results in a television receiver. These dimensions are, however, not to be regarded as limiting the invention, being given only by way of example.

What is claimed is:

1. The combination comprising a cathode ray tube, a magnetic deflection yoke positioned on the neck of said tube and a non-magnetic metallic strip extending longitudinally of the neck of said

tube, said strip extending between the neck of said tube and at least a portion of the width of said yoke.

2. The combination comprising a cathode ray tube, a magnetic deflection yoke positioned on the neck of said tube and a metallic, non-magnetic, longitudinally interrupted sleeve positioned on said neck and extending at least partly beneath said yoke.

3. In a cathode ray tube assembly comprising a cathode ray tube and a deflection coil yoke encircling the neck thereof; the combination therewith of a longitudinally interrupted, non-magnetic, metallic sleeve positioned on said neck and slidably therealong, a portion of said sleeve underlying said yoke.

4. In a cathode ray tube assembly comprising a cathode ray tube having a deflection coil yoke and a focus coil encircling the neck thereof; the combination therewith of a longitudinally interrupted, non-magnetic, metallic sleeve positioned on said neck and slidably therealong, a portion of said sleeve underlying said yoke, said sleeve extending beneath said focus coil and extending along said neck to a point between said focus coil and the base of said cathode ray tube.

5. Means for controlling the sweep amplitude of a cathode ray tube having a magnetic deflection yoke surrounding the neck thereof; said means comprising a non-magnetic metallic sleeve

having an interruption extending the full length thereof, said sleeve fitting around the neck of said tube beneath said yoke.
